HONING STONE AND METHOD OF
MANUFACTUREWilliam H. Harris, Jr., Detroit, Mich., assignor
to Micromatic Hone Corporation, Detroit,
Mich., a corporation of Michigan

Application February 13, 1950, Serial No. 144,008

11 Claims. (Cl. 51—204)

1

This invention relates generally to honing tools and more particularly to a honing element and a method of manufacturing the same.

It is an object of this invention to provide a honing element in which the honing stone or abrasive element is mounted and supported in a nonabrasive backing member, so that as the stone wears the encasing portion of the backing member will likewise wear, whereby the stone may be used until it is completely worn away, rather than replaced when only partially worn, such as is the case when metal backing members, or the like, are used to support the stone.

It is a still further object of this invention to provide a honing element of the aforementioned type, which may be easily and positively positioned in a grinding tool, and which is relatively inexpensive to manufacture and economical to use.

It is a still further object of this invention to provide a honing element of the aforementioned type, which is rugged in construction and durable in use, and in which the nonabrasive backing member is reinforced so as to reduce any danger of breakage or deformation of the element.

It is a still further object of this invention to provide a novel method of manufacturing a honing element of the aforementioned type, which method is extremely simple and inexpensive.

It is a still further object of this invention to provide a honing element of the aforementioned type, in which the backing member is made of a moldable material, such as plastic, so that the entire element can be molded together in one simple operation.

It is a still further object of this invention to provide a method of manufacturing honing elements, which permits a pair of honing elements to be simultaneously formed in a single mold and then severed or separated to produce a pair of either like or dissimilar honing elements.

These and other objects of this invention will become apparent from the following detailed description, taken in conjunction with the accompanying drawings, in which:

Figure 1 is a side elevational view, partially broken away in section, of a portion of a grinding tool having the honing elements of this invention connected therewith;

Fig. 2 is a sectional view of the structure illustrated in Fig. 1, taken along the line 2—2 thereof;

Fig. 3 is a perspective view of a honing element of this invention;

Fig. 4 is an exploded perspective view of a pair

2

of honing stones and a honing element reinforcing member prior to the assembly of these elements into a finished molded honing element;

Fig. 5 is a side elevational view of a portion of a mold having a pair of honing stones and a reinforcing member positioned therein;

Fig. 6 is a sectional view of the structure illustrated in Fig. 5, taken along the line 6—6 thereof;

Fig. 7 is a sectional view similar to Fig. 6, with the moldable material in the mold;

Fig. 8 is a perspective view of the article formed in the mold of Figs. 5 through 7, prior to the separation of the article into two honing elements; and

Fig. 9 is a view similar to Fig. 5, illustrating a further embodiment of the honing element of this invention, being formed in a mold.

Referring now to the drawings and more particularly to Fig. 3, a honing element 11 is illustrated, which includes a honing stone or abrasive element 13 and a nonabrasive backing member 15. The honing stone 13 has all but its working face 17 encased by the backing member 15, and the opposite sides of the backing member 15 have integral rectangularly shaped tabs or projections 19 formed thereon. In the particular embodiment illustrated, two such projections 19 are provided on each side of the backing member 15, and the projections extend rearwardly from the stone working face 17 to the back face of the backing member 15. Three longitudinally spaced grooves 21 are formed in each side face or wall of the backing member 15, and these grooves extend rearwardly from the working face 17 of the honing stone 13 to the back face of the backing member 15, for reasons which will hereinafter appear.

The top and bottom end walls of the backing member 15, rearwardly of the back face of the honing stone 13, are notched at 22, for reasons which will hereinafter appear. Imbedded in the backing member 15 are a pair of reinforcing members 23 and 25. The reinforcing member 23 is of an oppositely zigzagged shape, or has expanded or laterally offset portions 27, so that it is of substantially the same width as the honing stone 13. The reinforcing member 23 extends substantially the full length of the honing stone 13 and the front edge thereof engages the back face of the honing stone 13, while the back edge thereof terminates at the back face of the backing member 15. The reinforcing member 25 is in the form of a flat plate and has one side face thereof engaging one side of the reinforcing member 23. Member 25 is shorter than

55

member 23, so that it abuts only an intermediate portion of member 23.

Two honing elements, such as illustrated in Fig. 3, are simultaneously formed in a mold 29, such as illustrated in Figs. 5 through 7. The mold 29 is shown as being formed of two halves 31 and 33, which, when assembled, form a mold cavity 35. In forming the finished honing element, two honing stones 13 are placed in the mold cavity 35 and are spaced apart by the reinforcing elements 23 and 25, which, when inserted in the mold cavity, retain the opposed working faces of the honing stone in engagement with the end walls of the mold cavity. The opposite side walls of the cavity 35 are formed with three longitudinally spaced, laterally extending ribs 37, which engage the opposite side faces of the honing stones so as to maintain them in a spaced relation with respect to the side walls of the cavity. The side walls of the mold cavity 35 are also recessed at 39, at longitudinally spaced points, for reasons which will hereinafter appear. The cavity mold is then filled with moldable material, such as phenyl and vinyl resins and the like, which is of a nonabrasive character. A suitable molding operation is then performed so that the plastic or nonabrasive material forms a backing member encasing the reinforcing members and all but the working faces of the honing stones 13. The molded article is then removed from the mold, and is in the form illustrated in Fig. 8. By cutting the article illustrated in Fig. 8 along substantially the longitudinal center line 41, two honing elements, of the type illustrated in Fig. 3, are provided. The notches 22 are ground or cut in the top and bottom edges of the honing elements, either before or after the severing operation, so as to provide the finished elements.

The two honing elements formed from the one molded article illustrated in Figs. 5 through 8 are exactly similar. However, it is possible, with the method and construction of this invention, to form dissimilar honing elements such as illustrated in Fig. 9, wherein one honing stone 13' is of the same length as that previously illustrated, while the other honing stone 13'' is of a shorter length. With this arrangement, the honing stone 13'' is positioned with respect to the reinforcing member 23, by lancing tabs 43 from one side edge of the reinforcing member 23', which tabs will retain the honing stone 13'' in the proper relation to the reinforcing member during the molding operation. When the mold cavity is filled with moldable material, the space above and below stone 13'' will be filled with the material, which will wear at the same rate as the stone and will not interfere with the honing operation. The remainder of the method of forming the honing elements is the same as previously described, and when the molded article is longitudinally separated or cut two dissimilar honing elements are provided, one with a long stone and the other with a short stone.

In order to use the elements 11 in a honing operation, they are mounted in a suitable grinding or honing tool 44. The tool illustrated in the drawing comprises three longitudinally spaced spiders 45 which are recessed at 47, at circumferentially spaced points to receive a plurality of the honing elements 11. Cam shoes 49 are disposed in the slots 47 inwardly of the honing elements 11 and the cam shoes are engageable in a conventional manner by cam elements 51 so that the honing elements can be moved radially inwardly or outwardly relative to

the spiders. Garter springs 53 extend around the tool, at the upper and lower ends of the honing elements, and are positioned in the honing element notches 23 so as to resiliently hold the honing elements in position in the spiders. The projections or tabs 19 of the honing elements fit into recesses in the spiders 45 so as to prevent relative axial movement between the honing elements and the spiders. A plurality of wiper elements 55, which may be made of wood, plastic, or some other suitable nonabrasive material, are mounted in recesses in the spiders, at circumferentially spaced points, for the usual purpose.

It will thus be seen that the nonabrasive backing member 15 of each honing element can wear with the honing stone 13 and the honing elements need not be replaced until the entire honing stone is completely worn. Thus, the full benefit of the honing stone is achieved, and the honing element need not be repaired or replaced before the stone is completely worn, such as is generally the case with most honing element construction, where a nonabrasive backing member is not employed.

Furthermore, it will be appreciated that the projections or tabs on the honing element provide a simple means of positioning or anchoring the honing element in the honing tool, while the grooves or notches 22 provide a simple means for engagement with the garter springs which resiliently retain the honing elements in their proper position. Still further, the ribs 37 of the molds, which form the grooves 21 in the backing members, positively position the honing elements or stones in the mold and insure uniform molding of the material about the honing stone and reinforcing member. Also, as the greatest forces exerted on the honing element, during a honing operation, are in a radially inward direction, the zigzag construction of the reinforcing member 23 gives the necessary added strength and rigidity to the backing member 15 to prevent the same from materially deflecting, breaking or becoming damaged. Also, the reinforcing plate 25 aids in preventing deflection or bending of the entire honing element in the opposite plane. Thus, a durable, rigid, inexpensive honing element is provided, which is formed in one simple molding operation, and which is extremely inexpensive to manufacture and use.

What is claimed is:

1. A honing element for a grinding tool, including a honing stone unit, a backing and supporting member of molded plastic material encasing said stone on all but its working face, and a reinforcing member imbedded in said molded material and having one edge abutting against the adjacent face of said stone.

2. A honing element for a grinding tool, including a honing stone, a nonabrasive backing and supporting member encasing all but one face of said stone an edgewise disposed reinforcing member of sheet metal imbedded in said backing member behind said stone and extending in one direction from the back encased face of said stone to the back face of said backing member and substantially the entire length of said stone.

3. A honing element for a grinding tool, including a honing stone, a plastic backing and supporting member encasing all portions except the working face of said stone, a reinforcing member imbedded in said backing member behind said stone, said reinforcing member having portions laterally expanded or offset so that said reinfor-

ing member extends substantially the width of said stone.

4. A honing element for a grinding tool, including a honing stone, a plastic backing and supporting member encasing all portions except the working face of said stone, an oppositely zig-zagged reinforcing sheet metal element imbedded in said backing member behind said stone and extending substantially the width and length of said stone, one edge of said reinforcing element substantially engaging the back face of said stone, a second plate-like reinforcing element imbedded in said backing member behind said stone and adjacent to said first reinforcing element.

5. The method of making a honing element for a grinding tool, including the steps of positioning a reinforcing member between a pair of honing stones, of encasing said reinforcing member and all but the opposed faces of said honing stones with a plastic material, and of longitudinally cutting the article so formed so as to provide two honing elements.

6. The method of forming a honing element for a grinding tool, including the steps of positioning a pair of honing stones in a mold, positioning reinforcing means between said stones, of molding a material around and in engagement with said reinforcing member and stones so as to encase said reinforcing means and all but one face of each of said stones, of removing the articles so formed from the mold, and of longitudinally severing the article so as to form two honing elements.

7. The method of forming a honing element for a grinding tool, including the steps of positioning a pair of honing stones in the cavity of a mold, of separating the stones by positioning reinforcing means therebetween, of retaining the opposite side edges of said stones in spaced relation to the wall of said mold cavity, of molding material around said stones and reinforcing member so as to encase said reinforcing means and all but one face of each of said stones and produce a molded article, of removing said article from said mold, and of severing said article along its substantially longitudinal center line so as to provide two like honing elements.

8. An article of manufacture, including a pair of laterally spaced, longitudinally extending abrasive elements, one of which is of a substantially greater length than the other, a reinforcing member disposed between said abrasive elements for spacing the elements, means on one edge of said reinforcing member engaging the opposite end faces of the shorter of said abrasive elements for positioning the same with respect thereto, and a plastic backing and supporting member encasing all portions except the faces opposite to the adjacent faces of said abrasive elements and filling the space therebetween.

9. A method of simultaneously forming a pair of dissimilar honing elements for a grinding tool, including the steps of separating a pair of hon-

ing stones of different lengths with a reinforcing element of substantially the length of the longer abrasive element, of positioning the shorter stone relative to the longer stone by said reinforcing member, of encasing all but the faces opposite to the adjacent faces of each of said stones with a plastic material, and of severing the article so formed along its substantially longitudinal center line so as to provide two dissimilar honing elements.

10. A honing element for a grinding tool, including an abrasive element, a nonabrasive backing and supporting member of a substantially greater length than said abrasive element and encasing all portions except the one face of said abrasive element, a reinforcing member imbedded in said backing member behind said abrasive element and being of a substantially greater length than said abrasive element, and means on said reinforcing member engaging the ends of said abrasive element so as to retain the same in a predetermined position with respect to said reinforcing member.

11. A honing element for a grinding tool, including a honing stone of substantial length relative to its width and thickness, a unit backing and supporting case of molded plastic material encompassing said stone on all but its working face and being bonded thereto, said case at the ends and two opposite sides being comparatively thin so as to wear away as the abrasive material on the working face breaks down during the honing operation, the material on the side opposite to the working face being substantially thicker as compared with the thin material at the side and end walls, and a pair of rectangular-shaped tabs projecting from said opposite side walls, said tabs being spaced from each other and the ends of the element and aligned on opposite sides thereof.
